UNITED STATES PATENT OFFICE.

JOHANNES AUGUST OSENBRÜCK, OF HEMELINGEN, NEAR BREMEN, GERMANY.

STUFFING-BOX FOR AMMONIA COMPRESSION-PUMPS.

SPECIFICATION forming part of Letters Patent No. 300,886, dated June 24, 1884.

Application filed June 29, 1883. (No model.) Patented in Germany January 6, 1882, No. 17,373, October 31, 1882, No. 21,378, and January 5, 1883, No. 21,971; in England February 27, 1882, No. 982; in France May 13, 1882, No. 147,683, and in Austria-Hungary May 25, 1882, No. 12,817 and No. 20,241.

To all whom it may concern:

Be it known that I, JOHANNES AUGUST OSENBRÜCK, of Hemelingen, near Bremen, in the Empire of Germany, have invented certain new and useful Improvements in Stuffing-Boxes for Ammonia Compression-Pumps, (for which Letters Patent have heretofore been granted to me by the government of Germany, No. 17,373, dated January 6, 1882, No. 21,378, dated October 31, 1882, and No. 21,971, dated January 5, 1883; France, No. 147,683, dated May 13, 1882; Austria-Hungary, numbered, respectively, 12,817 and 20,241, dated May 25, 1882; and Great Britain, No. 982, dated February 27, 1882,) of which the following is a specification.

This invention relates to improvements in the stuffing-boxes for ammonia compression-pumps, and more especially to the compression-pump used in the Linde ice and refrigerating machine, in which glycerine is made use of as a liquid packing for preventing the escape of ammonia from the machine. As the glycerine is kept in said refrigerating-machine under the same pressure as the pump, it absorbs, owing to the high pressure and the comparatively low temperature, a considerable quantity of ammonia. In the working of the pump some of the glycerine which has absorbed ammonia adheres to a portion of the piston-rod when the same leaves the stuffing-box, so that the glycerine emits some of its ammonia, owing to the difference of pressure at the interior of the pump and the atmosphere. Though at each stroke of the piston a very small quantity of ammonia only is emitted, gradually a perceptible loss of ammonia takes place in course of time, owing to the large number of strokes of the piston.

The object of this invention is to overcome this loss of ammonia and to furnish a stuffing-box for ammonia compression-pumps in which the defect is obviated; and the invention consists of the combination, with the piston-rod and stuffing-box of an ammonia compression-pump, of an oil-chamber that is extended around the piston-rod and arranged with a heating device at the lower part for keeping the oil warm, a valved pipe connecting the

upper part of the oil-chamber with the suction-pipe of the pump, and a second stuffing-box by which the escape of oil from the oil-chamber is prevented.

In the accompanying drawings, Figure 1 represents a vertical longitudinal section of my improved stuffing-box for ammonia compression-pumps. Fig. 2 is an end elevation of the same, and Fig. 3 a vertical transverse section on line *x* *x*, Fig. 1.

Similar letters of reference indicate corresponding parts.

A in the drawings represents a stuffing-box for the piston-rod of an ammonia compression-pump. The stuffing-box is applied to the cylinder-head of the pump in the usual manner.

B is a rubber packing, that is placed around the sleeve *b* of an oil-chamber, *D*, and pressed tightly into the stuffing-box *A* by a lid, *C*, and screws *a a*, which turn in a flange, *a'*, of the oil-chamber *D*. By the packing *B* the escape of ammonia at the point where the stuffing-box *A* is connected to the oil-chamber is prevented. The oil-chamber *D* is filled with mineral oil neutral to ammonia—that is to say, which has no tendency to absorb ammonia-vapors. The oil-chamber *D* is provided at its opposite end with a stuffing-box, *E*, through which the piston-rod passes to the outside, as shown in Fig. 1.

At the lower part of the oil-chamber *D* a hollow cylinder, *F*, is arranged, into which a cylinder, *F'*, is inserted, through the lid of which passes a steam-induction pipe, *1*, while the water of condensation is conducted off through a pipe, *2*. The steam serves for the purpose of heating up the oil in the chamber *D*. The oil-chamber *D* is provided with an oil-gage, *D'*, (shown in Fig. 2,) by which the level of oil in the chamber is observed. Through the stop-cock *5* oil is forced from time to time into the oil-chamber *D*, to replace the oil spent in the working of the pump. The upper part of the chamber *D* communicates by a pipe, *6*, and socket *4* with the suction-pipe of the ammonia compression-cylinder, so that the oil which plays around the piston-rod of the pump is under the same pressure as the pump. The pressure-gage at the upper part of the oil-

chamber indicates the pressure in the same when the stop-cock 3 is opened.

By the heating device F the oil in the oil-chamber D is heated to such a temperature 5 that it cannot absorb any ammonia-vapors. It is thereby absolutely neutral against these vapors. The ammonia-vapors which escape through the stuffing-box A pass into the space G at the upper part of the oil-chamber, and 10 are conducted from thence through the pipe f to the suction-pipe and sucked off by the same. As the piston-rod of the pump passes through the hot oil, which forms a liquid packing for the same, and which is always free of ammonia, no vapors can therefore pass to the outside along the piston-rod, the hot oil forming 15 an absolutely tight and reliable packing against the escape of ammonia-vapors, even at a comparatively low pressure.

Having thus described my invention, I claim 20 as new and desire to secure by Letters Patent—

The combination, with the piston-rod and stuffing-box of an ammonia compression-pump, of an oil-chamber arranged around the piston-rod, a heating device at the lower part 25 of the oil-chamber for keeping the oil warm, a valved pipe connecting the upper part of the oil-chamber with the suction-pipe of the pump, and a second stuffing-box by which the escape of oil from the oil-chamber is prevented, sub- 30 stantially as set forth.

In testimony that I claim the foregoing as my invention, I have signed my name in the presence of two subscribing witnesses.

JOHANNES AUGUST OSENBRÜCK.
